ATTORNEY

UNITED STATES PATENT OFFICE.

RICHARD HERVIG, OF CHICAGO, ILLINOIS, ASSIGNOR TO AMERICAN CAR AND FOUNDRY COMPANY, OF NEW YORK, N. Y., A CORPORATION OF NEW JERSEY.

LATHE ATTACHMENT.

Application filed August 24, 1920. Serial No. 405,757.

To all whom it may concern:

Be it known that I, RICHARD HERVIG, residing at Chicago, in the county of Cook and State of Illinois, and being a citizen of the United States, have invented certain new and useful Improvements in a Lathe Attachment, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

20 In said drawings:

Figure 1 is a view in section of my improved device shown attached to a lathe, the machine head and tool support and operating means being shown in elevation;

25 Figure 2 is an end elevation;

Figure 3 is a plan view; and

Figure 4 is a section on the line 4—4 of Fig. 1.

It is the object of my invention to provide an improved device whereby a rotating work piece may be cut to an oval or elliptical cross section.

A further object is to provide an improved operating means for a device of the type described whereby a cutting tool is shifted to engage with the work when the work is shifted so as to be cut to an oval or elliptical cross section.

In the drawings, which show a modification of the device disclosed in my Patent No. 1,256,131, issued February 12, 1918, 1 designates the head and 2 the head spindle of the lathe or other machine to which my device is attached. The device itself comprises a tubular member 3 interiorly threaded for attachment to the spindle 2 and provided with recesses or keyways in which are placed the segmentally shaped keys 4, 4 and with diametrically opposed longitudinal guideways or faces 5, 5 disposed angularly to the axis of the member 2. Surrounding the tubular member 3 and loosely fitting the spindle 2 is a tubular member 6. The member 6 comprises a shell open at one end and provided at its other end with an end wall

7 having an outwardly extending annular projection 8 about the centrally located opening in the end wall 7. The shell of the member 6 is outwardly cylindrical but internally is eccentric to the axis of the member 6 in two directions whereby the inner surface of the member 6 contacts only with diametrically opposite arcuate portions of member 3, member 6 being, therefore, displaceable in opposite directions transversely of the inner tubular member 3. The member 6 is provided with slots adapted to register with the keyways of member 2 so that keys 4 when driven through the slots of member 6 and the keyways of member 3 will secure the members together.

With the members 3 and 6 so keyed together, they are held against relative longitudinal movement and the faces of the keys 4 which form the chords of the key segments form tracks bearing on the bottoms of the keyways in the tubular member 3. As the member 6 loosely surrounds the member 3, this arrangement of the keys allows the member 6 to be guidedly slid transversely of the spindle 2 and the inner member 3. It will be seen that the keys 4 will be rotated because of their engagement in the keyways of member 3 and will in turn rotate the member 6.

Surrounding the member 6 and slidable longitudinally thereof is an annulus 9 provided on its outer surface with an annular projection 10. Diametrically opposed countersunk holes in the annulus 9 receive screws 11 which pass through the annulus 9 and project into longitudinal slots 12 in the member 6 which register with the guideways 5 on the member 3.

Before the annulus is slipped over the member 6, guide blocks 13 are positioned in the slots 12 in the member 6 so as to bear against the guideways 5 and slide longitudinally thereof. These guide blocks 13 are secured to the annulus 9 by the screws 11 and move with said annulus. Surrounding the annulus 9 is a divisible coupling ring comprising sections 14 and 15 joined together by bolts 16 in the lugs 17 and 18 at the ends of the respective ring sections. The sections 14 and 15 secure the inwardly extending rings 19 and 20 which serve to confine the balls 21 which bear against the annular projection 10 on the annulus 9 thus forming a bearing which permits the annu-

lus 9 to rotate freely while the coupling ring is held against rotation.

Mounted in the opening in the end wall 7 of the member 6 is a tubular member 22 having an inner wall, cylindrical for part of its length and tapering inwardly for the remainder. Mounted in the member 22 and adapted to slide therein is a collet 23 having a projecting ring 24 at one end engaging the cylindrical portion of the wall and tapered at the other end to engage the tapering portion of the wall. The collet 23 is split into several pieces for the greater portion of its length so that upon being forced into engagement with the tapering portion of the wall the parts of the collet will be forced together and serve to grip the work piece. Between the collet 23 and the plunger 25 is the tubular member 26 having a ball and socket engagement with the collet 23 and with the plunger 25, the plunger 25 being operated in the usual manner to force the collet 23 forward to grip the work or to permit of the collet 23 being retracted to release the work. Mounted in the member 26 is the tubular guide member 27 having an enlarged head portion 28 that limits its insertion in the member 27.

Threaded on to the annular ring 8 is the face plate 29 provided with a projecting ring portion 30 that fits over the annulus 9 and serves to protect the interior of the chuck. Threaded into the sections 14 and 15 of the coupling ring are the projecting pins 31 and 32 provided with bushings 33 adapted to engage in irregular slots 34 in the cross pieces 35 and 36 of the cross slide and in the slots 37 in the members 38 and 39 bolted to the machine head. As shown in Fig. 3 the slots in the cross pieces 35 and 36 comprise central portions angularly disposed with respect to the longitudinal axes of the cross pieces and end portions parallel to the longitudinal axes and disposed on each side thereof while the slots 37 in the members 38 and 39 are parallel to the axis of the spindle 2. The ends of the cross pieces 35 and 36 are spaced apart by the upright tubular pieces 40 and 41 at the ends of the arms 42 and 43 projecting from the base piece 44 of the cross slide. Bolts 45 passing through the cross pieces 35 and 36 and the upright pieces 40 and 41 secure the cross pieces to the arms 42 and 43. The base piece 44 is adapted to slide, transversely of the machine bed, in a guide piece 46 mounted on the machine bed and is provided with a rack 47 engaged by a pinion 48 mounted on a shaft 49 that is rotated by means of a handle 50. Integral with the base piece 44 are the standards or tool supports 51 and 52 which carry the cutting tools 53 and 54 secured to the standards by the bolts 55.

In operation, rotation of the pinion 48

by means of the handle 50 will cause the cross slide, by means of rack 47, to move across in front of the chuck bringing one or the other of the tools 53 and 54 into engagement with the work piece 56 held by the chuck. It will, at the same time, move the slotted cross pieces 35 and 36 transversely of the machine head causing the slots 34, by engagement with the pins 31 and 32, to move the pins 31 and 32 longitudinally of the machine head in the slots 37 in the guide pieces 38 and 39 bolted to the machine head. The pins 31 and 32 carry with them the divided coupling ring which, through its engagement with the annular ring 10, operates the sliding annulus 9 and the guide blocks 13 longitudinally of the chuck. Movement of the guide blocks 13 along the guide faces will cause the guide blocks and annulus 9 to be shifted transversely of the chuck carrying with them the collet 23 and the work piece 56 mounted therein thus shifting the collet 23 and work piece 56 so that their axes will lie to one side of the axis of the spindle 2 and will be rotated around the axis of spindle 2 when the spindle is rotated. Operation of the handle 50 so as to move the cross slide in the opposite direction will bring the other cutting tool toward the work piece and will, at the same time, operate the pins 31 and 32, through their engagement in the slots 34, in the opposite direction in the slots 37 thus moving the annulus 9 and guide blocks 13 in the opposite direction and shifting the collet 23 and work piece 56 so that their axes will lie on the opposite side of the axis of spindle 2. Moving the cutting tools to a position in which they are equally spaced from the work piece will position the collet and work piece with their axes in line with the axis of spindle 2. The shifting of the tools and the collet can be done without stopping the machine.

What I claim is:

1. In a device of the class described, a machine spindle, a work holder carried by said spindle, a support for a tool engaging the work carried by said holder and an operating means for said tool support adapted to position said work holder eccentric to said machine spindle.
2. In a device of the class described, a plurality of tool supports, a work holder and an operating means adapted to simultaneously shift said work holder and move one tool support toward and the other tool support away from the work holder.
3. In a device of the class described, a machine spindle, a work holder carried by said spindle, a plurality of tool supports and operating means for said tool supports adapted to reciprocate said tool supports and to shift said work holder from one position eccentric of said spindle to another.

4. In a device of the class described, a cross slide, a tool support carried by said slide, a machine spindle, a collet chuck carried by the machine spindle and a connection 5 between said slide and said chuck adapted to move the collet eccentric to said spindle when said tool support is moved toward said chuck.
5. In a device of the class described, a 10 cross slide, a tool support carried by said cross slide, cross pieces operated by said cross slide, a machine spindle, a collet chuck carried by said machine spindle, sliding means adapted to position said collet eccentric to said machine spindle and a connection 15 between said sliding means and cross pieces adapted to operate said sliding means simultaneously with said tool support.
6. In a device of the class described, a machine spindle, a work holder carried by said spindle, a tool support, a carrier for said tool support and a connection between said carrier and said work holder adapted to shift said work holder eccentric to said machine spindle and said carrier transversely 25 of the machine simultaneously.
7. In a device of the class described, a machine spindle, a member secured to said spindle, a sleeve mounted on said member 30 for movement transversely thereof, a collet carried by said sleeve, a tool support, a carrier for said tool support and a connection between said carrier and said sleeve adapted to operate said collet and tool support simultaneously.
8. In a device of the class described, a machine spindle, a member secured to said spindle, a sleeve mounted on said member for movement transversely thereof, a collet 40 carried by said member, a plurality of tool supports, a carrier adapted to reciprocate said tool supports and a connection between said carrier and said sleeve adapted to move said sleeve in different directions as different tool supports are moved toward the collet.
9. In a device of the class described, a cross slide, a plurality of tool supports carried by said slide, a machine spindle, a collet 50 chuck carried by the machine spindle and a connection between said slide and chuck adapted to move said collet eccentric to said spindle in one direction when one tool support is moved toward said chuck and to move said collet eccentric to said spindle in another direction when another tool support is moved toward said chuck.
10. In a device of the class described, a cross slide, a machine head, a spindle carried by said head, a chuck carried by said spindle and having a collet adapted to be
- 65 moved transversely of said spindle, slotted members carried by said head and said cross slide and pins carried by said chuck and engaged in the slots of said members to operate said collet.
11. In a device of the class described, a machine spindle, a member secured to said spindle, a sleeve surrounding said member and adapted to be moved transversely thereof, an annulus movable longitudinally of said sleeve and adapted to operate said sleeve and a face plate carried by said sleeve and having a portion surrounding said annulus.
12. In a device of the class described, a machine spindle, a member secured to said spindle, a sleeve surrounding said member and adapted to be moved transversely thereof, a tubular member carried by said sleeve, 70 a collet mounted to reciprocate in said tubular member, a push rod mounted in said spindle and a flexible connection between said collet and said push rod.
13. In a device of the class described, a machine spindle, a member secured to said spindle, a sleeve surrounding said member and adapted to be moved transversely thereof, a tubular member carried by said sleeve, 75 a collet mounted to reciprocate in said tubular member, a push rod in said spindle and a member connecting said push rod and said collet and having a ball and socket engagement therewith.
14. In a device of the class described, a machine spindle, a member secured to said spindle, a sleeve mounted on said member for movement transversely thereof, a tubular member carried by said sleeve and a collet mounted to reciprocate in said tubular 80 member.
15. In a device of the class described, a machine spindle, a push rod therein, a chuck carried by said spindle and having a collet 90 carried by said spindle and a connection between said collet and said push rod adapted to permit said collet being positioned eccentrically of said push rod.
16. In a device of the class described, a machine spindle, a push rod therein, a chuck 95 driven by said spindle and comprising a collet adapted to be positioned eccentrically of said spindle and a connection between said collet and said push rod having a ball and socket engagement therewith.
- In witness whereof I have hereunto set my hand in the presence of two witnesses.
